W. H. McDONOUGH,
COMBINED REINFORCING PLATE AND KEY LUG FOR BRAKE SHOES.
APPLICATION FILED APR. 25, 1916.

1,227,282.

Patented May 22, 1917.

William H. McDonough, Inventor
By his attorney
Samuel G. Darby

UNITED STATES PATENT OFFICE.

WILLIAM H. McDONOUGH, OF NEW YORK, N. Y., ASSIGNOR, BY MESNE ASSIGNMENTS, TO THE AMERICAN BRAKE SHOE AND FOUNDRY COMPANY, OF WILMINGTON, DELAWARE, A CORPORATION OF DELAWARE.

COMBINED REINFORCING-PLATE AND KEY-LUG FOR BRAKE-SHOES.

1,227,282.

Specification of Letters Patent. Patented May 22, 1917.

Application filed April 25, 1916. Serial No. 93,362.

To all whom it may concern:

Be it known that I, WILLIAM H. McDONOUGH, a citizen of the United States, residing at New York city, in the county 5 and State of New York, have made a certain new and useful Invention in Combined Reinforcing-Plates and Key-Lugs for Brake-Shoes, of which the following is a specification.

10 The invention relates to brake shoes and particularly to the reinforcing back plate and key lug employed in connection with such devices.

15 The object of the invention is to provide an integral key lug and back plate for brake shoes, and means to reinforce the structure at the point where the key lug is formed.

20 Other objects of the invention will appear more fully hereinafter.

25 The invention consists substantially in the construction, combination, location and relative arrangement of parts, all as will be more fully hereinafter set forth, as shown in the accompanying drawing and finally pointed out in the appended claims.

Referring to the drawing:—

Figure 1 is a view in perspective showing a combined brake shoe back plate and key lug embodying my invention in one form 30 thereof.

Fig. 2 is a view in longitudinal section, on the line 2, 2, Fig. 1, looking in the direction of the arrows.

Fig. 3 is a view similar to Fig. 2, showing 35 a modified form of my invention.

It is a common practice in the manufacture of brake shoes to apply a reinforcing back plate of ductile metal, such as sheet steel, to the cast metal shoe body, and to 40 form a key lug for attaching the shoe to the brake head by transversely bending the back plate centrally into an integral loop with openings through the transversely extending walls of the loop for the passage of 45 the securing key. Such structure, however, interrupts the continuity of the back plate, leaving the space across the throat of the integral key lug unprotected and without reinforcement. As the greatest strains in use, 50 are imposed on the device at the key lug, it will be seen that in the construction referred to, and without reinforcement of the back plate across the throat of the key lug, the weakest part of the structure occurs at

the point where the greatest strains occur, 55 and this is most undesirable in devices of this nature.

It is among the special purposes of my present invention to provide a structure of back plate formed with an integral key lug, 60 and wherein reinforcement is provided across the throat of the key lug, and in a most simple and efficient manner, thereby avoiding the objections noted and securing added strength at the point where the greatest 65 strains occur.

In Figs. 1 and 2 I have shown one form of embodiment of my invention wherein 5 designates the metal back plate which, if desired, may be provided with the usual openings 6, therethrough to permit the metal of the cast shoe (not shown) to flush therethrough, in casting the shoe, to afford means for attaching the plate and shoe body together. Centrally of its length the plate is 70 transversely folded or bent to form the integral key lug 7, the transverse walls 8, 9, of which having alined openings 10, formed through the metal thereof for the passage of the brake head locking key. In this arrangement of key slots or openings it will be seen that the entire bearing of the key is taken by the metal of the key lug itself, and this is a practical advantage as it secures strength, the strains being transmitted 80 directly to the key through the key lug. 85

At the lateral or side edges of the key lug the back plate 5 is pressed outwardly into transversely extending off-sets or seats 11. Into these offsets or seats are received the 90 ends of a reinforcing tie plate 12, which extends across the throat of the key lug and ties together the parts of the plate lying on opposite sides of the key lug. By pressing the off-sets or seats 11 in the plate at opposite sides of the key lug and positioning the reinforcing tie plate therein the inner surface of said tie plate is brought into flush 95 relation with respect to the inner surface of the back plate. This reinforcing tie 100 plate may have one or more openings 13, therethrough for the metal of the cast shoe body to flush through in casting the same to afford means for attaching the tie plate to the shoe body.

In the form shown in Fig. 3, the reinforcing tie plate 14 is centrally pressed outwardly to form an extension 15 which ex- 105

tends outwardly and partially into the throat of the key lug 7, to afford an additional reinforcement of the key lug and to aid in taking the strains of usage. One or 5 more openings 16, may be formed through the outwardly pressed extension 15 of the tie plate for the same purpose as the openings 6, 13, above referred to.

It will be understood that the reinforcing 10 tie plate may be secured to the back plate if desired, and in any desired manner.

Having now set forth the objects and nature of my invention and various forms of embodiment thereof, what I claim as new 15 and useful, and of my own invention, and desire to secure by Letters Patent, is,—

1. A back plate for brake shoes bent up transversely to form an integral key lug, said plate having outwardly pressed portions 20 adjacent the sides of said lug to form

seats on its inner surface, and a tie plate received in said seats and spanning the throat of said lug.

2. A back plate for brake shoes bent up transversely to form an integral key lug, 25 and a reinforcing plate extending across the throat of said lug, said tie plate lying flush with the inner surface of said plate.

3. A reinforcing rack for brake shoes consisting of a plate with an outwardly 30 formed integral key lug, the inner surface of said plate adjacent the sides of said lug provided with seats, a tie plate received in said seats and spanning the throat of said lug.

35 In testimony whereof I have hereunto set my hand on this 20th day of April A. D., 1916.

WILLIAM H McDONOUGH.
